UNITED STATES PATENT OFFICE.

EDGAR W. ANTHONY, OF BROOKLINE, MASSACHUSETTS.

HOT-AIR FURNACE OR HEATER.

No. 918,812.

Specification of Letters Patent.

Patented April 20, 1909.

Application filed October 22, 1906. Serial No. 339,955.

To all whom it may concern:

Be it known that I, EDGAR W. ANTHONY, of Brookline, in the county of Norfolk and State of Massachusetts, a citizen of the 5 United States, have invented a new and useful Improvement in Hot-Air Furnaces or Heaters, of which the following is a full, clear, and exact description, reference being had to the accompanying drawings, forming 10 a part of this specification, in explaining its nature.

The essential object of my invention is to provide a furnace of a simple and compact structure with as large an area of heat- 15 radiating surface as possible, and to direct the currents of air over said heat-radiating surface or surfaces.

My invention accordingly consists in various details of construction all of which 20 can be seen and understood by reference to the drawings, in which—

Figure 1 shows the furnace in vertical section. Fig. 2 shows a plan of the furnace with the dome or head thereof removed. 25 Fig. 3 shows in side elevation the radiator forming one of the essential elements of the improved furnace construction. Fig. 4 shows a cross section on the line 4—4 of Fig. 1, and Fig. 5 shows in side elevation 30 one of the radiator plates to which special reference will hereinafter be made.

Referring to the drawings:—A represents the exterior casing or wall of the furnace. On this is mounted the hood or dome A¹ 35 having exit passages *a* for the escape and distribution of hot air. *a*¹ represents the fire-pot within which is formed the combustion chamber *a*². Entrance into the fire-pot is by way of the feeder *a*³ controlled by 40 a door *a*⁴ forming a portion of the exterior wall of the furnace. *a*⁵ represents the grate having the grate rod *a*⁶. Beneath the grate is an ash-pit *a*⁷, entrance to which is controlled by the door *a*⁸ forming a portion of 45 the exterior wall of the furnace.

Surmounting the fire-pot is a radiator A² connecting with the interior of the combustion chamber. Through this radiator the products of combustion are directed to pass 50 and ultimately escape through an outlet pipe *a*⁹, as will hereinafter be explained. This radiator together with the fire-pot furnishes the means for heating air which rises from the cold air chamber *a*¹⁰ formed between the shell or wall of the furnace and 55 the fire-pot and escapes through the exit

passages *a* in the hood or dome of the furnace.

The radiator A² is preferably of annular structure, made relatively deep. It is also 60 preferably made in two parts *a*¹¹, *a*¹² connected by a common cup jointure *a*¹³.

The products of combustion are supplied to the radiator from the combustion chamber by the smoke arm *a*¹⁴ which connects 65 with an extension *a*¹⁵ to the fire-pot. This extension *a*¹⁵ forms practically a portion of the fire-pot, but for convenience it is referred to as an extension thereto. It is secured to the fire-pot by a cup jointure *a*¹⁶. 70 It is also to be noted that both the extension *a*¹⁴ and the smoke arm *a*¹⁵ are contained within the inclosure of the radiator. The radiator is supported by the fire-pot or rather extension thereto through the 75 interposition of the smoke arm *a*¹⁴. The smoke arm connects with the upper portion *a*¹¹ of the radiator, the lower portion *a*¹² thereof being secured to the upper portion by means of lugs *a*¹⁷ joined by screws or 80 other mode of fastening. The radiator is supported in such position that ample air space will be left between it and the exterior casing of the furnace. Its position relatively to the fire-pot is such that a somewhat restricted air passage will be formed 85 between it and the fire-pot in order that the air which enters through this passage to course upwardly through the inclosure of the radiator will not pass too quickly. 90 Other means for supporting the radiator auxiliary to that above described may be employed if necessary. Attention is also called to the fact that the lower portion of the radiator is cut away in part at *a*¹⁸ in 95 order to clear the feeder *a*³.

After the products of combustion or heat has passed up through the extension *a*¹⁵ and smoke arm *a*¹⁴ into the radiator, it is made to pass through the radiator before escaping 100 through the smoke or outlet pipe *a*⁹ by means of a direction-plate *a*¹⁹ which is located diagonally crosswise the radiator at a point adjacent to the outlet pipe *a*⁹. In 105 this plate is located a damper *a*²⁰. The bottom part of the radiator is also provided with one or more clean-outs *a*²¹ each of which is closed by a cap *a*²². Access to each of the clean-outs is had through the adjacent outer wall of the furnace by an opening *a*²³ closed by a cap *a*²⁴.

With the parts arranged as above de-

scribed, a large amount of heat-radiating surface is provided for heating the air from the cold air chamber. The outer side of the radiator will act to heat that air contained 5 in the space between the radiator and the shell of the furnace. Both the fire-pot and radiator will act to heat the air which enters the somewhat restricted passage formed between these respective parts. The air entering this passage will pass upwardly through the inclosure of the radiator and there be subjected to heat provided by the radiating surfaces afforded by the inner side of the radiator on the one side and the extension 10 to the fire-pot on the other. It will also encounter the smoke arm acting as a further heat-radiating surface. For the purpose of providing a still greater heat-radiating surface the upper portion of the radiator is 15 formed with a series of deep recesses or openings a^{25} extending down from the top thereof and crosswise through the same. In order that the air which rises along the outer side of the radiator may be directed to flow into 20 these recesses or openings and over the heat-radiating surface thus formed the top of the air-passage leading from the cold air chamber a^{10} alongside the outer surface of the radiator and into the head or dome of the 25 furnace, is closed by a plate or rather a series of plates a^{26} held together by flanges and screws a^{27} .

The plate or plates a^{26} , annular in form or arrangement, extend from the outer wall of 30 the furnace at a point substantially flush with the upper part of the radiator over onto the same, closing said air-passage and directing air to pass into and over the radiating surfaces formed by the recesses or openings 35 a^{25} in the radiator. The plate or plates a^{26} act also to baffle the air preventing it, in other words, from flowing directly into the head or dome of the furnace from the cold air chamber and causing it to be retarded 40 along the outer heating surface of the radiator before being directed to flow through the radiator in the recesses or openings formed therein. The deep indentations a^{25} besides providing a large amount of auxiliary heat-radiating surface, perform also a 45 still further and important function. In a radiator like the one described, made relatively deep, the tendency of the heat rising would be to flow in and around the top of the radiator to the exclusion of the bottom thereof, which would not receive its adequate 50 amount of heat. Now it is very necessary that the bottom part of the radiator should be properly heated, for there the radiator 55 first receives the impact of the cold air. The recesses or openings formed in the upper portion of the radiator perform the function of causing the heat entering the radiator to flow around the bottom part there-

of on which account the entire radiator becomes properly heated. 65

In order to provide a still further heat-radiating surface there are shown interposed between the radiator on the one side and the extension a^{15} on the other a series of preferably corrugated plates a^{28} . They are preferably made loose, hanging dependent from flanges a^{29} resting upon indented lugs a^{30} formed upon the top of the radiator and the extension a^{15} , respectively. On account of 70 these plates being snugly interposed between the radiator and the extension a^{15} from the combustion chamber they become intensely heated and so provide auxiliary heat-radiating surfaces both for the air which rises from 75 the cold air chamber between the radiator and the walls a^{15} forming a portion of the extension from the combustion chamber and for the air which is directed to pass through the transverse recesses or openings in the 80 radiator. The plates a^{28} perform, also, the function of providing a more equal distribution of air by causing the air to flow up in a series of passages instead of through one annular passage, if the plates were removed. 85 Under certain atmospheric circumstances the air sometimes has a tendency to rise more upon one side of the furnace than upon the other, and these plates by providing a series of passages prevent such unequal distribution of the cold air. 90

Having thus fully described my invention, I claim and desire to secure by Letters Patent of the United States:—

1. In a furnace or heater of the character specified, the combination of an outer casing and inside the same a fire-pot, a radiator 100 surmounting the fire-pot and so located relatively to said fire-pot and casing that air may course upwardly over said radiator on both the inner and outer sides thereof, said radiator having also transverse recesses or 105 openings therein, an extension to said fire-pot, a connection between it and the inner side of said radiator whereby the products of combustion are directed from the fire-pot 110 to pass into and through said radiator, said extension and connection being located within the inclosure of said radiator and forming heat-radiating surfaces to the air 115 coursing upwardly over the inner side of said radiator, and means for baffling the air and directing it to pass up over said radiator on the outer side thereof to pass through the transverse recesses or openings therein and 120 be heated by the auxiliary heat-radiating surfaces afforded thereby.

2. In a furnace or heater of the character specified, the combination of an outer casing and inside the same a fire-pot, a radiator 125 surmounting the fire-pot said radiator having transverse recesses or openings therein and located relatively to said fire-pot to

- form a restricted air passage between it and the fire-pot through which passage air is admitted to course upwardly to pass through the inclosure of the radiator and be heated 5 by the inner radiating surface thereof, a connection between said radiator and fire-pot for directing the products of combustion to pass from said fire-pot into and through said radiator, said connection being located 10 within the inclosure of said radiator and providing an auxiliary heat-radiating surface to the air passing upwardly through the inclosure of the same, and means for baffling the air coursing upwardly over the 15 outer side of said radiator and directing it to pass through the transverse cuts or openings therein and be heated by the auxiliary heat-radiating surfaces afforded thereby. 3. In a furnace or heater of the character 20 specified, the combination of an outer casing and inside the same a fire-pot, a radiator surmounting the fire-pot and so located relatively to said fire-pot and casing that air may course upwardly over said radiator on 25 both the inner and outer sides thereof, said radiator having also transverse recesses or openings therein, an extension to said fire-pot, a connection between it and said radiator whereby the products of combustion 30 are directed from said fire-pot to pass into
- and through said radiator, a series of plates radially interposed between said radiator and the extension from the fire-pot providing auxiliary heat-radiating surfaces, and means for baffling the air passing upwardly 35 over the outer side of said radiator and directing it to pass through the transverse cuts or openings therein whereby it may be heated by the auxiliary heat-radiating surfaces afforded by said transverse cuts or recesses and said interposed plates. 4. In a furnace or heater of the character specified, a fire-pot having an extension, a radiator surrounding said extension, and a smoke-pipe connecting said extension with 45 said radiator whereby the products of combustion may enter said radiator, said radiator also being located whereby an air passage is formed between said radiator and the extension from said fire-pot, and a series 50 of loose plates interposed between said radiator and the extension from the said fire-pot for directing the air currents and providing auxiliary heat-radiating surfaces substantially as described.
